UNITED STATES PATENT OFFICE.

HARRY McCREARY, OF INDIANA, PENNSYLVANIA.

DESIGN FOR A BROAD-TREAD TIRE.

Application filed May 29, 1925. Serial No. 13,603. Term of patent 3½ years.

To all whom it may concern:

Be it known that I, HARRY McCREARY, a citizen of the United States, residing at Indiana, in the county of Indiana and State of Pennsylvania, have invented a new, original, and ornamental Design for a Broad-Tread Tire, of which the following is a specification, reference being had to the accompanying drawing, forming a part there-of.

Figure 1. is a side elevation; and Fig. 2. is a perspective view of a portion of a broad-tread tire, showing my new design.

I claim:

The ornamental design for a broad-tread tire, as shown.

HARRY McCREARY.
